UNITED STATES PATENT OFFICE.

AMOS L. FOREMAN, OF YORK, PENNSYLVANIA.

BOTTLE-CRATE.

1,290,157.

Specification of Letters Patent.

Patented Jan. 7, 1919.

Original application filed November 13, 1916, Serial No. 131,121. Divided and this application filed October 7, 1918. Serial No. 257,260.

To all whom it may concern:

Be it known that I, AMOS L. FOREMAN, a citizen of the United States, residing in York, Pennsylvania, have invented certain 5 Improvements in Bottle-Crates, (the same being a division of my application, Serial No. 131,121, filed November 13, 1916,) of which the following is a specification.

My invention consists of certain improvements in the bottle crate forming the subject of my previous Letters Patent No. 1,050,823, dated January 21, 1913, the object of my present invention being to securely connect the ends of the transverse bottle- 15 separating strips of the crate to the sides of the crate without the use of nails.

This object I attain in the manner herein- 20 after set forth, reference being had to the accompanying drawing, in which— Figure 1 is a transverse vertical section of a bottle crate constructed in accordance with my present invention;

Fig. 2 is a vertical section, on a larger scale than Fig. 1, of part of one of the sides 25 of the crate and of the connection between the same and the end of one of the transverse strips of the bottle separator, and

Fig. 3 is a perspective view, on a still larger scale, of one of the elements of said 30 connection.

The frame of the crate is of rectangular form, the ends 1 having bottom strips 2 and the sides being composed of upper and lower strips 3 and 4. The bottom of the 35 crate consists of a wire 5 carried back and forth between the bottom end strips 2 and let into recesses in the tops of said strips, as clearly set forth in my previous Patent No. 1,050,823.

The ends of the longitudinal separator 40 strips 11 may be secured to the end members 1 of the crate in any available manner, for instance, in the manner set forth in my previous application Serial No. 131,121, filed November 13, 1916, my present invention, 45 which is a division of that referred to, having reference solely to the means employed for fastening the opposite ends of the transverse separator strips 12 to the opposite sides of the crate.

The end portions of these strips fit be- 50 tween the upper and lower members 3 and 4 of the sides of the crate, and each end is perforated for the reception of the dowel pin 13 which projects both upwardly and downwardly from the strip and is em- bedded, respectively, in the upper and lower members 3 and 4 of the sides of the crate, these dowels therefore serving not only to firmly secure the end portions of the trans- 55 verse strips 12 to the sides of the crate but also to prevent separation of the upper and lower members 3 and 4 of said sides.

In order to better attain the latter object the dowels 13 may be notched or recessed on 60 each side, as shown at 13^a in Figs. 2 and 3.

I claim:

The combination of the opposite sides of 70 a bottle crate with a transverse bottle-sepa- rating strip having its opposite ends project- ing into the opposite sides of the crate and having at each end a dowel pin which pro- jects above and below the strip and is em- bedded in the corresponding portions of the side of the crate.

In testimony whereof, I have signed my name to this specification.

AMOS L. FOREMAN.
